SMOKING PIPE

Filed June 25, 1936

UNITED STATES PATENT OFFICE

2,144,393

SMOKING PIPE

Milton Schnaier, New York, N. Y.

Application June 25, 1936, Serial No. 87,134

9 Claims. (Cl. 131—203)

My invention relates to improvements in smoking pipes, and the same has for its object to provide a pipe which is simple in construction and efficient in operation.

5 Further, said invention has for its object to provide a pipe in which the oils and distillates released or produced in the course of smoking are abstracted or removed from the smoke before the smoke reaches the mouth piece of the pipe.

10 Further, said invention has for its object to provide a pipe which includes a fluid absorbing element or cartridge capable of being readily removed, replaced or renewed.

Further, said invention has for its object to 15 provide a pipe in which the fluid absorbing element thereof extends directly into the smoke conducting passage for filtering the smoke, absorbing the liquid constituents thereof and conducting the same into the outer portion of the element 20 lying beyond said passage.

Further, said invention has for its object to provide a pipe which includes a chamber in heat 25 receiving relation to the bowl and communicating with the smoke passage or duct for receiving a cartridge for absorbing the liquids and causing the evaporation thereof.

Further, said invention has for its object to 30 provide a pipe in which the absorbent element or cartridge within said chamber serves to effectively close or plug the same so that the smoke may be drawn through the pipe from the bowl and filtered without detrimental effect due to the venting of said chamber into said smoke conducting passage.

35 Further, said invention has for its object to provide a pipe in which the bowl has a perforated partition forming a smoke chamber within the bowl below said partition in advance of the liquid absorbing element for protecting the absorbent material against undue contamination from the tobacco, ash or other solids within the bowl.

Further, said invention has for its object to 40 provide a pipe which includes means for mechanically engaging the absorbent cartridge for initiating the withdrawal thereof from its chamber.

Further, said invention has for its object to 45 provide a pipe in which said cartridge withdrawing means includes a pintle having operating means therefor and in which said pintle may serve as a hinge pin for a pivoted cover on the pipe bowl.

Other objects will in part be obvious and in part be pointed out hereinafter.

55 To the attainment of the aforesaid objects and

ends my invention consists in the novel features of construction, and in the combination, connection and arrangement of parts hereinafter more fully described and then pointed out in the claims.

In the accompanying drawing—

5 Figure 1 is a side elevation of one form of pipe constructed according to and embodying my said invention;

Fig. 2 is a longitudinal section thereof;

Fig. 3 is a plan thereof showing the cover open; 10

Fig. 4 is an enlarged section thereof on the line 4—4 of Fig. 2;

Fig. 5 is a detail sectional view showing a modified form of mounting for the hinged cover and cartridge withdrawing means; 15

Fig. 6 is a plan thereof with the cover in open position;

Fig. 7 is a detail section on the line 7—7 of Fig. 3, and

Fig. 8 is an enlarged detail section of the cover 20 supporting means shown in Fig. 5.

In said drawing 10 designates the bowl of the pipe which is substantially cylindrical in outline and has a rounded base 11. The bowl 10 is provided with a central opening 12 having a 25 shoulder 13 near its lower end upon which is supported a perforated bottom plate or partition 14 forming a smoke chamber 15 at the bottom of the bowl 10. The smoke chamber 15 improves the combustion and prevents the formation of 30 gummy deposits within the pipe.

The bowl 10 has its wall at the rear enlarged throughout its height to form an extension portion 16 having a cylindrical opening or receptacle 17 extending entirely through said portion 16 35 in position to be heated by the bowl, and having its lower end communicating with the smoke conducting passage or bore 18 provided in the stem 19 which communicates at one end with the smoke chamber 15. The bore 18 at the outer end 40 of the stem 19 is enlarged to form a socket 20 into which is fitted the reduced end 21 of the mouth piece or bit 22.

Within the receptacle 17 is disposed a cylindrical filter or absorbing element or cartridge 23 45 preferably made of compressible absorbent cotton or other suitable material, and of such size that the same will completely fill the said receptacle or opening 17 when squeezed into said receptacle. 50

Upon the top of the bowl 10, and partly surrounding the upper end of the opening or receptacle 17 is a hinge plate 24 which is secured in place by pins 25. The plate 24 is provided with 55

an aperture 26 which registers with the opening 17 in the extension 16.

The plate 24 is provided with rolled-over portions or knuckles 27 pivotally supporting a hinge pin or pintle 28 having a spur or prong 29 fixed centrally thereof for engagement with the cartridge 23. The pintle 28 is adapted to be partially rotated by a finger portion 30 extending from one end thereof when it is desired to remove 10 the cartridge 23.

The pintle 28 also serves as a pivotal mounting for a cover 31 having apertures or perforations 31^a therein. The cover 31 is preferably detachably secured to a member or tongue 32 15 having knuckles 32^a engaging the pintle 28. The tongue 32 is provided with a T-shaped opening 33 in the relatively enlarged outer end portion thereof beyond the reduced intermediate portion 34. The cover is provided with a projecting 20 tongue portion 36 having the angularly directed lugs 37 thereon adapted to engage the opposite edges of the reduced portion of the cover, and the projecting hook portions 38 adapted to be received within the reduced portion of the opening 33. Upon sliding movement of the cover upon 25 the tongue 32 towards the outer end thereof, the hook portions 38 interlock with the reduced end portion of the tongue 32, the larger end portion of the opening 33 providing clearance for 30 said hook portions 38.

In Figs. 5, 6 and 8 is illustrated a modified form of mounting 24^a for the perforated cover 31 and cartridge engaging member 29. In this form the upper end of the cartridge receiving chamber 17 is enlarged at 17^a for receiving the externally threaded tubular member or sleeve 24^a registering with the opening 17. The member 24^a has formed thereon the split bearing portions 40 for rotatably supporting the pintle 28 having the spur 29 rigidly secured thereto and also pivotally supporting the cover 31 for movement independently of the pintle. The cover 31 preferably comprises the resilient hook portions or knuckles 41 adapted to engage the pintle 28 for pivotal movement thereon, and to be readily disengaged therefrom when it is not desired to use the cover.

In either form of the invention, the elongated absorbent element or cartridge 23 extends at its lower end partway into the duct or smoke conducting passage 18 to form a filter or screen transversely of the duct. The remaining portion of the cartridge 23 substantially fills the opening 17 in close fitting relation thereto to substantially close the same against the ingress of air through said passage 17 and into the duct 18 when smoke is being drawn from the bowl 10 into the mouth. The distillates, oils or other liquids contacting with the lower end of the cartridge 23 are gradually thereby absorbed upwardly into the portions of the material within the receptacle 17, freeing the smoke from undesirable constituents for delivery in a dry clean state to the mouth. The duct 17 is in heat-conducting relation to the bowl 10 so that as the liquid is drawn upwardly through the filtering material 23 the moisture therein is rapidly evaporated preventing the material from becoming excessively soggy.

The provision of the partition or plate 14 and the smoke chamber 15 prevents the blocking up or clogging of the duct 18 at the entrance thereto by tobacco packed into the bowl 10, and the contamination of the absorbent material by the tobacco within the bowl or by the ash resulting 70 from the combustion. Smoke may thus be readily

drawn through the duct 18 and filter 23 without undue restriction of the flow thereof and without material venting of air through the passage 17 otherwise liable to reduce the quantity of air drawn into the bowl 10.

The cartridge 23 in cylindrical form may be readily inserted into the opening 17 through the open end thereof in position to function as an absorbent with the pivoted spur 28 caught or engaged with upper end of the cylinder. When 10 the lower end of the cartridge becomes saturated, the same may be readily withdrawn by rotating the spur 29 upwardly by the finger piece 30 and partially withdrawing or extracting the cartridge from the chamber 17 so that the same 15 may be readily seized by the fingers to completely withdraw the same. If so desired, the withdrawn cartridge may be inverted and replaced in position with the unsaturated portion thereof extending into the passage 18. A clean cartridge 20 is substituted when the one in use becomes saturated or unfit for use. The cover 31, when closed and locked at 42, serves as a closure for both the open end of the receptacle 17 and for the bowl 10. Said cover prevents the escape of sparks and 25 ash, and also allows the pipe to be smoked with the open end of the bowl in inverted position. The cover may be opened and closed by a pivotal movement upon the pintle 28 without dislocation of the spur 29 from operative position, and may 30 be readily removed if it is not desired to use the same.

By my invention I am able to obtain a substantially dry smoke without impairing the normal operation of the pipe or unduly complicating 35 the structure thereof. By the provision of a relatively elongated absorbent cartridge 23 the liquids contacting with the lower end thereof are absorbed into the upper portion thereof so that said lower end is capable of functioning for an 40 appreciable time in absorbing the liquids and transmitting the same to the upper portions of the cartridge where the same may be evaporated by the heat of the bowl. Whenever desired the position of the cartridge may be reversed to expose the less permeated portion thereof to the 45 smoke drawn through the duct 18.

Having thus described my said invention what I claim and desire to secure by Letters Patent is:

1. A smoking pipe comprising a bowl, a tubular portion extending from said bowl, a receptacle 50 extending through the wall of said bowl from without into said tubular portion, an absorbent element within said receptacle, movable means for closing the outer end of said receptacle, and means engageable with said element at the outer end thereof for extracting the same.

2. A smoking pipe comprising a bowl, a tubular portion extending from said bowl, a receptacle arranged at one side of said bowl and communicating at its base with the draft bore in said tubular portion, an absorbent element in said receptacle, a cover pivotally secured to the open end of said bowl, and means associated with said cover for extracting said absorbent element. 60

3. A smoking pipe comprising a bowl, an extension on said bowl, a receptacle in said extension, a tubular portion extending from the base of said bowl and communicating with said receptacle, an absorbent element in said receptacle, and means pivotally mounted upon said bowl adjacent the open end of said receptacle for extracting said absorbent element therefrom. 65

4. A smoking pipe comprising a bowl, a stem extending from the base of said bowl and hav- 75

ing a smoke conducting passage, a receptacle in the wall of said bowl extending downwardly from the top thereof into said passage, an absorbent element in said receptacle, a closure pivotally secured to the open end of said bowl for covering the open end of said bowl and the outer end of said receptacle, and means associated with the pivotal mounting for said closure and movable independently of the closure for extracting said absorbent element.

5. A smoking pipe comprising a bowl, a stem extending from the base of the bowl, a receptacle in the wall of said bowl communicating with said stem, an absorbent element in said receptacle, a mounting upon the open end of the bowl, a pintle having a spur for extracting said element pivotally supported upon said mounting, and a cover pivotally mounted upon said pintle.

6. A smoking pipe comprising a bowl, a tubular portion extending from said bowl, an opening formed in the wall of said bowl and extending from the top thereof into said tubular portion, a sleeve secured within said opening at the outer end thereof, knuckle portions on the outer end 15 of said sleeve, a pintle pivotally mounted on said knuckle portions and having a spur thereon, an absorbent element within said opening adapted to be extracted by said spur, and a cover having resilient portions detachably engaging said pintle 20 for pivotal movement thereon.

7. A smoking pipe comprising a bowl having a receptacle formed in the wall thereof and open at the top, a stem extending from said bowl and having a passage in communication with said receptacle, an absorbent element in said receptacle, means movably mounted upon said bowl for closing the same, and the outer end of said receptacle, and means, associated with said means for closing said bowl, operable independently thereof for effecting the extraction of said ele- 10 ment.

8. A smoking pipe comprising a bowl having a receptacle formed in the wall thereof and open at the top, a stem extending from said bowl and having a passage in communication with said receptacle, an absorbent element in said receptacle, and a spur pivotally mounted upon said bowl adjacent to the open end of said receptacle for engagement with said element to extract the 15 same.

9. A smoking pipe comprising a bowl, a receptacle in the wall thereof open at the top, a stem extending from said bowl in communication with said receptacle, an absorbent element in said receptacle, a mounting upon the open end of the bowl, and a pintle having a spur for extracting said element pivotally supported upon said mounting.
